(57) **CLAIM**

The ornamental design for a bucket, as shown and described.

DESCRIPTION

FIG. 1 is a perspective view showing the new design for a bucket;

FIG. 2 is a front view thereof, a rear view being a mirror image thereof;

FIG. 3 is a left side view thereof;

FIG. 4 is a right side view thereof;

FIG. 5 is a bottom view thereof;

FIG. 6 is a top view thereof;

FIG. 7 is a perspective view thereof showing the bucket with a Wringer; and,

FIG. 8 is a cross-sectional view taken along line 8-8 of FIG. 5. The broken lines in the drawings are shown for illustrative purposes only and form no part of the claimed design.
